UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

COAL DRILL.

Application filed April 19, 1921. Serial No. 462,727.

To all whom it may concern:

Be it known that I, NILS D. LEVIN, a citizen of the United States, residing at Columbus, in the county of Franklin and State of Ohio, have invented certain new and useful Improvements in Coal Drills, of which the following is a specification, reference being had therein to the accompanying drawing.

10 The present invention relates to certain new and useful improvements in coal drills of the class adapted to form incisions in the coal body for the reception of the charges of explosive by which the coal is blasted down. 15 The especial object is to provide a convenient, light and durable drill supporting and actuating mechanism, arranged to guide the drill to form incisions in any one of a large variety of positions, and by which the 20 rate of advance of the drill tool may be varied according to the hardness of the coal.

The devices by which I attain these objects are fully set forth in the following 25 specification and illustrated in the accompanying drawings of which

Fig. 1 is a side elevation of the preferred embodiment of my invention adjusted to form an incision in the coal near the top 30 of the vein.

Fig. 2 is a plan view, and

Fig. 3 is a front elevation of the mechanism illustrated in Fig. 1.

Fig. 4 is a fragmentary plan view on an 35 enlarged scale of the sliding carriage by which the drill actuating motor is movably supported upon the supporting frame.

Fig. 5 is a sectional view taken along the line V—V of Fig. 4.

40 Fig. 6 is a sectional view taken along the line VI—VI of Fig. 4.

Fig. 7 is a sectional view taken along the line VII—VII of Fig. 4.

Fig. 8 is a sectional view taken along the 45 line VIII—VIII of Fig. 4.

Fig. 9 is a detail of the drill feeding mechanism.

Fig. 10 is a side elevation, similar to Fig. 1, showing the apparatus adjusted to form 50 an incision in the coal near the base of the vein.

Like numerals refer to similar parts in the several figures.

As shown in the drawings, the supporting 55 frame comprises a post 1 and a slide way 2,

adapted to be held in adjustable relation to each other and to the coal in which blast holes are to be drilled. The post 1 is formed of two parallel angle bars 3 joined together at their ends by steel blocks 4 and 5 to which 60 they are secured in any preferred manner, as for example, by electric welding. The bottom block 5 is pierced by a longitudinal aperture in which the bottom point 6 is longitudinally slideable, and by a transverse 65 aperture through which the locking pin 7 extends to engage any one of the apertures 8 of the bottom point 6 to lock it in the preferred position of longitudinal adjustment. The top block 4 is provided with a 70 longitudinal aperture in which the top point 9 is screw threaded, a cross bar 10 being provided for its convenient manipulation. By the adjustment of the bottom and top points 75 6 and 9 the post 1 may be securely anchored between the floor and the roof of the mine in any preferred position relative to the coal face.

Formed in the angle bars 3 are a plurality of spaced apertures 11 through which may 80 be thrust the connecting pins 12 and 13. The connecting pin 12 is adapted to engage a suitable aperture near the inner end of the guide way 2, and the pin 13 is adapted to similarly engage a suitable aperture at the 85 inner end of the brace 14. The outer end of the brace 14 is connectable to the guide way 2 by a pin 15 extending through one of the spaced apertures 16 in the guide way 2. By the arrangement of parts just described the 90 guide way 2 may be rigidly connected to the post 1 at any preferred angle and at a variety of elevations.

The guide way 2 is formed of two parallel 95 angle bars 17 connected together by suitable cross members 18 and 19. Formed in the cross member 19 at the inner end of the guide member 2 is a saddle 20 in which the forward end of the drill tool 21 may be loosely supported and guided.

The drill tool 21 is of a type well known in the coal mining art, having a cutting edge at its inner end and a helicoid body adapted to draw the cuttings outwardly of the drill hole. At its outer end the tool 21 is shaped 105 to engage a socket 22 directly connected to the armature shaft of a suitable electric motor 23. Electric current for the actuation of the motor 23 is received from any convenient source of electrical supply through the 110

conductor cable 24, and is controlled by a suitable switch 25 in the manner well understood in the art. The motor 23 is mounted upon a carriage 26 which is slidably longitudinally of the guide ways 2, and this motor is securely held in place upon the carriage by U bolts 27 the ends of which extend through suitable apertures in the cross bars 28. The carriage 26 comprises a base plate 29 adapted to slide upon the upper surface of the horizontal flanges 30 of the angle bars 17, and to this base plate 29 are attached, in any suitable manner such as by electric welding, riveting, or the like, the flange strips 31 which engage the inner edges and lower surface of the horizontal flanges 30 to prevent accidental displacement of said carriage. To the base plate 29 are attached the upwardly extending flanges 32 in the rearward end of which are formed open, longitudinally extending notches 33 at the inner ends of which the shaft 34 of the feeding mechanism may find a bearing. To the shaft 34 are attached two rollers 35 upon the peripheries of which are formed sprocket teeth 36 adapted to engage spaced apertures 37 of the horizontal flanges 30 to serve as a pinion and rack for moving the carriage forwardly upon the guide way. A crank 38 attached to the shaft 34 affords means to rotate the pinions 35, and the leverage of said crank 38 may be adjusted to vary the pressure exerted by the feed shaft 34 upon the carriage. Rollers 39, attached to the underside of the carriage, engage the underside of the horizontal flanges 30 to insure engagement of the sprocket teeth 36 with the apertures 37.

Preparatory to operation, the supporting post 1 is set in the preferred position in proximity to the coal face, and securely anchored by the adjustment of the top and bottom points 6 and 9. The guide way 2 is then placed at the desired elevation and the connecting pin 12 inserted through the preferred aperture 11. The brace 14 is then adjusted to hold the guide way 2 in the preferred angular relation to the supporting post 1. The carriage 26 is then placed upon the guide way 2 and the drill 21 inserted in the sockets 22 with its forward end resting in the saddle 20. After starting the motor 23 the carriage will be pushed forward to cause the drill 21 to engage the coal to cut it. If the coal be relatively soft the pressure of the operator's hand upon the motor 23 will be sufficient to force the drill into the coal at a suitable rate of advance. If, however, the coal is harder than can be conveniently cut by the pressure of the hand against the motor, the feeding pinion 35 may be placed in position upon the guide angles 30 with the sprocket teeth 36 engaging the apertures 37, and rotated to cause the shaft 34 to enter and find a bearing in the bearing notches 33. Rotative pressure upon the hand crank 38

will tend to revolve the pinion 35 to force the sliding carriage 26 forwardly to feed the drill into the coal. By the adjustment of the length of the crank 38, as provided for by the slotted aperture 40, the leverage 70 may be varied to produce a pressure upon the drill point proportionate to the hardness of the coal. After the hole has been drilled to the desired depth the feed shaft 34 may be removed, the sliding carriage 26 and motor 23 drawn rearwardly of the guide way and removed therefrom, the post 1 and guide way 2 disassembled, after which the drill tool 21 may be withdrawn from the hole by the hand of the operator. 80

As stated, I provide an apparatus by which drilling can be effected in materials varying widely in their hardness and resistance to the cutting action. For very hard coal or other substance to be drilled, a powerful motor can be used, together with strong, heavy feeding devices and a heavy supporting frame; and yet the several parts are separable to such an extent that they can be readily manipulated when they are to be lifted to or taken from their working positions. And after being assembled the tool is universally adjustable. 85

If the material to be drilled is soft and less resisting, a number of the parts of the entire apparatus can be dispensed with. The motor is separable from the carriage and is so constructed that it can be readily put into operative position, as it does not require any particular positioning in respect 100 to its axis. It fits into its support or holder no matter how it is angulated around its axis, and can be rigidly fastened in whatsoever position it assumes. There is no bodily stationary gearing supplemental to the motor shaft and, no matter what position it assumes, if it lies in proper transverse planes, there is no interference with its operative relation either to the drill or the other devices. 110

Again, the mechanism by which the power for feeding is transmitted is readily separable from the carriage, or motor support, and the motor. As above explained, when the material is relatively soft the rotary feeding devices may be dispensed with and the advance of the drill effected by the pushing force of the operator's hand; when the line of the work is inclined downward the weight of the essential parts is often sufficient. 120

What I claim is—

1. In a drilling machine, the combination of a frame having spaced apart guide rails, a motor carriage slidably mounted on said guide rails, a motor detachably secured to said carriage, a drill operatively connected with said motor, independent carriage moving means removably and rotatably mounted in open bearings in rear of said motor carriage, and means on said guide rails en- 130

gaged by said carriage moving means to advance itself and said motor carriage on said guide rail.

2. In a drilling machine, the combination 5 of a frame having spaced apart guide rails provided with a series of tooth engaging sockets, a motor carriage slidably mounted on said guide rails, a motor detachably secured to said carriage, a drill operatively connected with said motor, a rotary shaft 10 having toothed drive wheels removably mounted in open bearings in rear of said motor carriage with its drive wheels engaged with the sockets on said guide rails, 15 and means for rotating said shaft to advance it and said motor carriage along said guide rails.

3. In a drilling machine, the combination of a frame having spaced apart guide rails provided with tooth receiving apertures, a 20 motor carriage slidably mounted on said guide rails, journal blocks having open bearings at their rear ends on either side of said carriage, a motor detachably secured to said carriage, a drill operatively connected with 25 said motor, a manually operable shaft removably mounted in the open bearings of said journal blocks in rear of said carriage, and toothed wheels carried by said shaft and engaging the apertures in said guide 30 rails to advance said shaft and motor carriage on said guide rails.

In testimony whereof, I affix my signature.
NILS D. LEVIN.
